UNITED STATES PATENT OFFICE.

EDWIN D. BELKNAP, OF EAST ORANGE, NEW JERSEY.

PRINTING MECHANISM.

1,208,268.

Specification of Letters Patent. Patented Dec. 12, 1916.

Application filed May 6, 1914. Serial No. 636,811.

To all whom it may concern:

Be it known that I, EDWIN D. BELKNAP, a citizen of the United States of America, residing at East Orange, county of Essex, 5 State of New Jersey, have invented certain new and useful Improvements in Printing Mechanism, of which the following is a specification.

My invention relates generally to machines for printing with the aid of stencils, and the particular embodiment of the invention here shown comprises a hand operated rotary addressing machine employing stencil cards.

15 Heretofore stencil printing machines have been constructed with ink reservoirs in which a body of fluid ink was stored, and from which the ink was gradually transferred to the rolls or platen which, in co- 20 operation with the stencils, did the printing. This body of fluid ink has always been a source of trouble and difficulty, especially in the case of small machines designed to be sold to the public and operated by inexpert 25 persons, in that it is liable to spill or to dry up or collect dirt and gum up with age so that the machine ceases to operate satisfactorily. When a new body of such ink is prepared by a user inexperienced in the 30 printer's art, it is rarely of the right consistency and character. Moreover it is impracticable to ship a machine to the customer with the ink in the reservoir, and unless an expert is sent to put the ink foun- 35 tain and apparatus in operative condition, the customer is apt to have trouble with the ink from the start. My invention over- 40 comes these difficulties by substituting for the usual ink fountain, doctor roll, etc., a simple roll of absorbent felt which, I have discovered, will hold enough ink when saturated to last through tens of thousands of 45 printing operations. When the supply of ink contained by the felt roll is ultimately exhausted, a new or recharged one can easily be substituted, and another long period of uninterrupted usefulness secured for the machine. In the case of the owners 50 of small hand machines the fresh rolls of felt saturated to the right degree by the expert manufacturer with ink of exactly the right description can be shipped to users and inserted in the machine by any person without requiring any skilful manipulation. 55 The particular machine embodying my invention and shown in the accompanying

four sheets of drawings also presents certain other novel and improved features hereinafter to be pointed out.

In the drawings: Figure 1, is an elevation of the machine looking at the right hand side, with parts broken away. Fig. 2, is a plan view. Fig. 3, is a vertical longitudinal section taken on line 3—3 of Fig. 2. Fig. 4, is a detail side elevation of the stencil card receptacle. Fig. 5, is a vertical cross section taken on line 5—5 of Fig. 1, with parts broken away. Fig. 6, is a detail plan view of the card feeding slide, with parts broken away, and Fig. 7, a detail vertical sectional view of the same taken on line 7—7 of Fig. 6.

Throughout the drawings like reference characters indicate like parts.

1, is the main frame having legs cast 75 thereon and terminating preferably in rubber tips 2, 2.

3, is the stencil card magazine at one end of the machine and above the level of the printing apparatus, while 4, is the card receptacle at the other end of the machine, located below the level of the line of discharge of the stencil cards from the printing apparatus. These cards travel in the well known way along the card guides 5, 35 from the magazine 3, to the receptacle 4, being intermittently driven by the card feeding slide 6, provided with claw 50, which is reciprocated back and forth under the card magazine in the grooved guides 51, 80 by means of the cross bar 7, having an upwardly projecting ear to which the connecting rod 8, is pivoted. The other end of the connecting rod is pivoted to the crank disk 9. This crank disk has handle 29, and hub 95 39, by which it is mounted on the driving shaft 10, of the machine. The crank disk is held on the shaft 10, by the screw bolts 37, 37, passing through the retaining washer 36, and the hub 39, into gear 23, which is fastened upon shaft 10, by one of the set screws 46. The mechanism is covered and supported largely by the cast metal cover plate 11, which extends from the card magazine to the card receptacle and has the semi-cylindrical portion 54, closed at one end 17, and having an approximately semi-circular opening at the other end which is closed by the crank disk 9, this portion of the construction serving as a protecting housing 105 for the upper member of the hereinafter to be described printing mechanism. This

cover plate 11, also has the vertical partition 13, cast in it and on this is cast the journal sleeve or hub 12, serving as a bearing for the shaft 10, and the journal sleeve 14, serving as a bearing for another shaft 15, which carries a transfer roll 20, which is usually made of metal preferably with a facing of rubber.

19, is an inking sector mounted on the 10 shaft 10.

16, is a supplemental journal sleeve for shaft 10, cast on the back plate 17, and 18, is a similar supplemental journal sleeve for shaft 15. The sector 19, and roll 20, rotate 15 between the ends of these journal sleeves. The outer end of shaft 15, has a gear 24, meshing with gear 23, and fastened to the shaft 15 by one of the set screws 46, passing through the hub 44.

20 21, is a platen sector mounted on the shaft 22, journaled in the main frame 1, and provided on its outer end with the gear 25, meshing with the gear 23. This gear 25, is held on shaft 22, by one of the set screws 25 46, passing through the hub 45.

28, is a rotatable ink pad composed of a section of thick, highly absorbent felt cut out in circular form and mounted on shaft 30 in cover panel 31, which is hinged so 30 as to cover the opening in the top of the semi-cylindrical portion 54, of cover plate 11, by means of hinge pin 32. The free end of the swinging panel 31, is controlled by the compression screw 34, mounted in the 35 threaded lug 35, on the cover plate 11. The swinging panel 31, preferably has an approximately semi-cylindrical recess 33, in which the rotatable ink pad 28, is journaled. The card guides 5 are located as shown so 40 that the line of travel of the cards through them will be tangential to both the inking sector 19, and the platen sector 21, when the same rotate into contact.

26, is a table supported by the main frame 45 1, slightly below the level of the card guides 5, but above the level of the shaft 22, of the platen sector, and slotted to permit the platen sector to rotate through it.

40, is a guide for envelopes or other articles 50 on which printing is to be done. This consists of a vertical strip carried by the guide rod 42, which engages a downward projection from the strip which passes from the slot 41, in the table 26. The guide rod 42, 55 is adjustable in the lug 46, and can be held in any position by the set screw 47.

48, is a downwardly projecting pin at the outer end of the guide strip which serves 60 as a handle by which the guide may be adjusted inwardly or outwardly.

27, indicates the outline partly in dotted lines of an envelop being run through the machine and 38, represents in dotted lines, the outline of a stencil card being run 65 through the inking mechanism.

The operation of the device is as follows: A series of stencil cards being stacked in the magazine 3, the operator grasps the crank handle 29, with his right hand, and rotates the same in the direction to produce 70 the rotation of the co-operating sectors indicated by the arrows in Fig. 3. This reciprocates the card feeding slide 6, and the claw 50, pulls out the stencil card at the bottom of the magazine at each reciprocation, and feeds the same along to the inking mechanism. The operator pushes the envelop, or other article to be printed, along the envelop guide 40, and in between the sectors 19, and 21, at the time their cut-away 80 portions are turned inwardly. When the full portions of these sectors rotate to the inner position they seize the stencil card and the envelop between them and force them along, at the same time pressing the film of 85 ink on the surface of the inking sector 19, through the stencil perforations onto the envelop beneath. During a portion of each rotation the inking sector 19, is in contact with the rotating ink transfer roll 20, and 90 has its supply of ink replenished therefrom. This transfer roll is at all times in contact with the rotatable ink pad 28, and the amount of ink transferred from the pad to roll 20, is regulated by turning the set screw 95 34. When the rotatable ink pad ceases to perform its functions, through age or exhaustion of the ink, the hinged panel supporting it can be turned upward or removed altogether, and a new ink pad placed 100 in it.

The advantages of my invention comprise its simplicity, the moving parts being reduced to the least possible number, its self-contained construction by which all the 105 mechanism is protected from dirt and the operator is protected from possible contact with inked surfaces, and the total elimination of the objectionable ink fountain.

Various changes can be made in the form 110 of the parts and the transfer roll 20, might be dispensed with and the construction thereby further simplified.

Much depends in the successful use of my invention on the selection of the best 115 form of most highly absorbent felt as the material out of which the rotatable ink holding element is to be made. I find that, so far as I am at present advised, the best results are to be obtained from the article 120 known in the trade as medium soft Spanish woolen felt.

Having described my invention, I claim:

1. In a stencil printing machine the combination with an inking device comprising a 125 pair of rotating inking and platen members, a reciprocating card feeding slide and guides therefor, of a casing for the inking members, an actuating crank mounted on the shaft of one of the above recited pair 130

of rotating members, a handle on said crank exterior of said casing, and a connecting rod pivoted to said handle and to the card feeding slide.

- 5 2. In a stencil printing machine the combination with a rotary inking device provided with a driving shaft, reciprocating card feeding slide, and a casing for the inking device having an approximately semi-circular opening on one side, of a crank disk mounted on the driving shaft of the inking device and closing said opening, and a connecting rod pivoted to said crank disk and reciprocating slide.
- 10 3. The combination of a casing of approximately semi-cylindrical shape open at one end but closed at the other and having an interior cross partition with hubs extending therefrom at right angles thereto, shafts 15 journaled in said hubs, a set of inking rolls mounted in the closed end of the casing on said shafts, intermeshing gears mounted on

the outwardly projecting ends of the shafts and a crank disk mounted on one of the shafts and closing the before mentioned 25 opening in the casing.

4. In a stencil printing machine the combination of a pair of rotating elements comprising an inking sector and coöperating platen sector, means for rotating the two 30 sectors, a protecting housing for the upper member of said pair of rotating elements, means for feeding stencils along a line tangential to the meeting line of said sectors, and a feed table located slightly below 35 the line of feed of the stencils and the lower edge of the housing and slotted to permit the lower sector to project upward through it, together with an envelop guide mounted on said table.

EDWIN D. BELKNAP.
